UNITED STATES PATENT OFFICE.

CLARENCE H. CRAIG, OF BOULDER, COLORADO.

SASH-BALANCE.

No. 931,007.

Specification of Letters Patent.

Patented Aug. 10, 1909.

Application filed September 9, 1908. Serial No. 453,253.

To all whom it may concern:

Be it known that I, CLARENCE H. CRAIG, a citizen of the United States of America, residing at Boulder, in the county of Boulder and State of Colorado, have invented certain new and useful Improvements in Sash-Balances, of which the following is a specification.

This invention relates to new and useful improvements in sash balances and has for its object to provide a spring actuated device which combines simplicity of construction with great practicability in use and by means of which the upper and lower sashes of a window may be automatically and independently balanced and retained at any desired elevation.

Further objects of my invention reside in the provision of a spring which renders the vertical movement of the sashes equable and of a means whereby the sashes are rendered self adjustable when they are in their lowermost position.

I attain these objects by the mechanism illustrated in the accompanying drawings in the various views of which like parts are similarly designated and in which—

Figure 1 is a vertical sectional view of the window casing with the sashes and the balancing means in operative position. Fig. 2 a horizontal section taken along a line 2—2 Fig. 1. Fig. 3 a vertical section through the upper portion of the window frame looking toward one of its sides. Fig. 4 a detail of the spring employed in the invention. Fig. 5 a fragmentary sectional view of the window frame and one of the sashes, showing the means whereby the latter is suspended. Fig. 6 a face view of the fastening means shown in Fig. 5. Fig. 7 a sectional view of one of the winding drums with the cord in the position in which it is when the sash is in its lowermost position.

Referring to the drawings by numerals, let the reference character 2 designate the window frame, the upper portion 3 of which incloses a chamber 4 which extends into the sides of the frame. Secured upon the top board 5 of the frame within the chamber 4 and in central relation to the former, is a hollow post 6 upon which are mounted two identical winding drums 7. Each drum consists of two parallel disks which are connected by means of a plurality of equidistant upright pins 8 which are integral with the lower one and riveted into corre-

sponding apertures of the upper one. The pins 8 constitute collectively the working face of the drum upon which is wound the sash cord or chain from which the sash is suspended. The lower drum is designed to balance the lower sash, while the upper one is connected with the upper sash of the window and the cords or chains 9 are connected with the respective drums by being passed around a trundle 10 which is secured between the parallel disks of the drum at a point outside its working face. After the middle portion of each cord has been passed around the respective drum and the therewith associated trundle, in the manner illustrated in Fig. 7 of the drawings, its oppositely extending ends are passed over guide rollers 12, which are rotatably mounted at the extreme ends of the chamber 4, through openings in the top board 5, and are secured to the sides of the corresponding sash.

The means by which the extremities of the cords are fastened are shown in Figs. 5 and 6 and consist of a leaf-spring 13 which is secured within the sash groove by means of a screw or nail 14 and which is formed in its upper extremity with an aperture to receive a hook 15 which is fastened to the end of the cord or chain. The lower portion of the spring 13 is curved outwardly to frictionally engage the opposite surface of the guide way in the window frame through which the sash moves and the spring is thus employed, not only to prevent rattling of all fitting sashes, but to aid in retaining the sash in its adjusted position.

Within each of the drums 7 is a coil band spring 16 the extremities of which are respectively secured within a groove in the post 6 and to one of the connecting pins 8, and this spring, which has been shown in detail in Fig. 4, is thickest at its innermost extremity from where it is gradually thinned towards its opposite end. The object of the peculiar construction of the springs is to render the movement of the sash which is balanced thereby, equable irrespective of the latter's elevation as will hereinafter be explained and in connection with this feature of my invention, I wish it understood that, if so desired the spring 16 may be made of even thickness and gradually narrowed from its inner to its outer extremity.

When one or the other of the two sashes comprised in a window is in its lowermost

position, the cord or chain 9 engages, as is shown in Fig. 7, one half the circumference of the trundle 10 and the opposite half of the winding face of the drum which, as 5 stated hereinbefore, is formed by the pins 8 which connect the parallel disks of the drum and are arranged concentrically with respect thereto. The cord 9, in this position, is free to adjust itself, should the sash to which its 10 ends are attached, be out of its proper adjustment and it will thus be observed that by these means the danger of binding of the sashes within the guide grooves of the frame is obviated, their even movement assumed 15 and the careful adjustment of the cords required in other devices of this class rendered unnecessary. The spring which, when the sash is in its highest position is entirely or partly relaxed, is wound during downward 20 movement of the sash and by its tension retains the latter at any desired elevation in which function it is aided by the frictional contact of the springs 13 with the window-casing. As each convolution is wound upon 25 the other the power of the spring increases, so that the effort required to lower the sash becomes continually greater as the sash descends. If the spring were composed of a band of even flexibility it would have to be 30 made sufficiently weak to permit young or feeble persons to operate the window, in which case its qualities to retain the sash in its adjusted position, would be materially impaired, and if made of sufficient strength 35 to adequately perform this last-named function, the window could be manipulated only by those physically able to overcome the tension of the spring. By constructing the spring of a coiled band whose flexibility 40 gradually increases from its inner to its outer extremity, as shown and described, the variation in the tension of the spring, while being wound or unwound, is rendered less noticeable and its strain upon the sash is 45 substantially even irrespective of the latter's position in relation to the window frame so that the movement of the sash is equable and easy while the spring is of sufficient strength to retain the latter in its adjusted position.

50 Having thus described my invention what I claim is:—

1. The combination with a window-casing and a sash slidably mounted therein, of a

horizontal spring-actuated drum having a trundle beyond its working face a rope or 55 chain whose ends are secured at opposite sides of the sash, wound upon the drum in engagement with the trundle so that when the said sash is in its lowermost position the said cord or chain is free to adjust itself 60 longitudinally, irrespective of the drum.

2. The combination with a window casing and upper and lower sashes slidably mounted therein of a vertical post secured above the said sashes at equal distances from their 65 sides, upper and lower wheels rotatably mounted upon the said post, springs within the wheels one of their ends being secured thereto while their opposite ends are fastened to the post, guide rollers above the side 70 faces of the said sashes, a continuous rope or chain wound around each wheel its ends extending oppositely therefrom, the rope or chain connected with the upper wheel being secured at its ends to the upper sash and that 75 connected with the lower wheel having its extremities fastened to the lower sash.

3. The combination with a window-casing and a sash slidably mounted therein, of a hollow vertical post secured above the latter 80 at equal distance from its sides, a wheel rotatably mounted upon the post and composed of parallel disks connected by pins which are integral with one and riveted to the other and arranged concentrically with 85 reference thereto, a spring having its ends secured respectively to one of the said pins and in a slot of the said post, and a cord or chain wound in engagement with the said pins, its oppositely extending ends being 90 secured to the said sash.

4. The combination with a window casing and a sash slidably mounted therein, of a horizontal spring actuated drum revolvably secured above the said sash at equal distances 95 from its sides and a continuous rope or chain wound around the said drum its oppositely extending ends being secured at opposite sides of the sash.

In testimony whereof I have affixed my 100 signature in presence of two witnesses.

CLARENCE H. CRAIG.
